[57] CLAIM

The design for an end cap for medical tubing, as shown and described.

DESCRIPTION

FIG. 1 is a perspective view of an endcap for medical tubing showing my new design;

FIG. 2 is a top plan view thereof;

FIG. 3 is a side elevational view thereof, with all other side elevational views being identical thereto;

FIG. 4 is a bottom plan view thereof; and,

FIG. 5 is a cross-sectional view thereof, taken along the line 5—5 of FIG. 2.

FIG. 1

FIG. 3

FIG. 2

FIG. 5

FIG. 4
